UNITED STATES PATENT OFFICE.

SARAH K. RAMER, OF VANCOUVER, BRITISH COLUMBIA, CANADA.

CARD GAME.

Application filed May 4, 1927. Serial No. 188,864.

This invention relates to a card game using slightly modified playing cards of the traditional type or others of similar relative value.

5 The object of the invention is to provide a card game for four players or any multiple thereof, which has a widened scope of interest and which includes factors of surprise and combination which are in excess 10 of usual card games.

The figure shows four typical cards of the deck.

The game may be played with a single deck of fifty-two cards, each player receiving thirteen dealt in the usual way and each player playing for himself alone.

The position of each player is drawn for and carries with it the determination of his particular trump designation, each player 20 having his own suite of trumps, i. e., a suite having a ruling value. For instance the dealer always has hearts as his trumps, the next player sits to left of dealer and has clubs as his trumps, the next player or the 25 one opposite the dealer has diamonds and the fourth player spades.

This peculiarity of four sets of trumps in simultaneous operation but limited in its effect to each individual player is a unique 30 feature of the game.

The cards are selected and played successively into a single pile and the object of the game is that each player rids himself of all his cards as quickly as possible and his 35 endeavours are directed towards the best way of compelling his fellow players to take them.

The mode of the play is thus:—The player next and left of the dealer commences playing any one card only, the next in turn must follow suite with a card of higher value or failing this must play a card of his own trump suite. Should any player be unable to follow suite or trump he must take into 45 his hand whatever pile of cards has accumulated. However should he desire at any time to take the pile instead of play his turn he is at liberty to do so.

When a player has either played a card in suite or as a trump, he plays another card (an arbitrary selection) to be dealt with by the next player exactly as described for the

second player, and so on until the game is finished by the first, second and third player 55 dropping out respectively each having successively disposed of the whole of his cards.

Thus each player except the first at the commencement plays two cards (according to rule) or takes into his hand the accumulated pile of cards on the table.

Should any player find himself with but one card at his turn of play, and that card being of the necessary value to enable him to play his turn, he must take the accumulated pile of cards, which in this case are withdrawn and cancelled from the game, so leaving the remaining players with a depleted deck to conclude, he himself retaining the winning position at that point of the 70 game.

From the above it will be observed that there is an arbitrary designation of trump suites determined by the position of the players and therefore that each trump is 75 linked in interest to another trump, i. e., the trump suite of the next player in turn against whose play the player's skill is especially directed with a view to drawing out his trumps. With this peculiarity in view it is convenient to double corner-index the cards for this game in such a manner that the corresponding card of the trump suite of the next player is shown below the usual corner-index. For example the dealer in the game always has hearts as trumps, and the succeeding players clubs, diamonds and spades respectively, therefore on the hearts suite the second corner-index should be clubs, the club suite—diamonds, the diamonds suite—spades, and the spades suite— 80 hearts.

In this way any player notes his next 85 player's trumps at the same time he notes his own, his next player being his chief opponent.

From the above description it will be seen that the double turn to each player, the quadruplicated trump system together with the cumulative risk, are factors which working in combination provide, a culmination 90 of intense and increasing interest.

Having now fully described my invention what I claim as new and desire to be protected in by Letters Patent, is:

A card game comprising a deck of conventional monarchical playing cards having the four conventional heart, club, diamond, and spade suits, each of said suits being an arbitrarily assigned trump for each particular playing position, and each of the cards having, in addition to its own main corner index, an extra corner index, said extra cor-

ner index indicating the trump suit assigned to the playing position following the playing position to which the main index is assigned as trump. 10

In testimony whereof I affix my signature.

SARAH K. RAMER.
